UNITED STATES PATENT OFFICE.

WILLIAM R. BAKER, OF WATERTOWN, NEW YORK, ASSIGNOR TO THE HITCHCOCK LAMP COMPANY, OF SAME PLACE.

SHOWER-BATH APPARATUS.

SPECIFICATION forming part of Letters Patent No. 608,947, dated August 9, 1898.

Application filed November 13, 1897. Serial No. 658,369. (No model.)

To all whom it may concern:

Be it known that I, WILLIAM R. BAKER, a citizen of the United States, residing at Watertown, in the county of Jefferson and State 5 of New York, have invented certain new and useful Improvements in Shower-Bath Apparatus; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to improvements in shower-bath apparatus, and especially to the provision of a perforated pipe made in such a shape as to allow of its being hooked about the neck or limb of a person, whereby it may 20 be easily and quickly adjusted in place and readily removed from the person, if desired, while the water is being brought to a suitable temperature for a shower-bath.

More specifically the present invention relates to a shower-bath apparatus which will 25 be an improvement upon the objectionable circular sprayers commonly in use and which consists of a hook-shaped perforated pipe which is of such a shape as to conform to the 30 contour of the neck of a person adjacent to the shoulders, so that it may be held in place of its own weight, one end of the said pipe being closed, while its other end may be connected to a hose-pipe, the series of perforations in the pipe being on the under curved 35 portion thereof.

In the use of a shower-bath apparatus of the nature above referred to it is necessary that the temperature of the water be adjusted 40 while the tube is in its adjusted place about the neck or other part of the person, and, in case hot water is turned on first, to avoid the scalding of the person the peculiar shape of the present invention will allow of its being 45 withdrawn from the neck of the person and not cause any inconvenience to the head of the person or burn the face, as would be likely to be the case if the pipe were made in the

shape of a ring, necessitating its going on over the head and its removal in the same manner. 50

My invention is clearly illustrated in the accompanying drawings, which, with the letters of reference marked thereon, form a part of this application, and in which drawings—

Figure 1 is a perspective view showing the 55 improved sprayer or shower-bath apparatus as applied to a person, the perforated tube being hooked about the neck of said person. Fig. 2 is an enlarged detail view of the tube.

Reference now being had to the details of 60 the drawings by letter, A designates the sprayer-tube, which is closed at one end, as at A', and is bent of the general shape shown in the drawings, so that it will fit over the shoulders of the wearer and about the neck, 65 as shown in Fig. 1 of the drawings. In order to enable the tube A to settle in position upon the neck of the person using it, the two ends of the tube are turned downward, as shown in Fig. 1, so as to rest upon the front portion 70 of the chest, whereby all necessity of holding the tube is entirely done away with. As the tube is bent so as to conform to the curvature of the body it sinks in position as soon as it is placed around the neck, and 75 hence requires no adjusting. The ends of the tube are a sufficient distance apart so as to allow the tube to be hooked about the neck, which renders it easy to adjust in place and remove. About the under curved surface of 80 the tube is a series of apertures a, and at the opposite end is formed the ribbed portion, over which a hose-pipe may be drawn.

By this improved form of shower-bath apparatus it will be noted that a lady may hook 85 the tube about her neck while the water is turned on and still not wet her hair, which is impossible to do with the circular sprayer rings.

Having thus described my invention, what 90 I claim to be new, and desire to secure by Letters Patent, is—

A shower-bath apparatus consisting of a U-shaped tube A, having one of its prongs longer than the other and provided with 95 means for attaching the hose thereto, and

which is provided with a series of perforations on its under side, and which tube has its two ends curved downward so as to rest upon the chest of the person using it, and
5 whereby the tube is made to automatically adjust itself in position, substantially as shown and described.

In testimony whereof I affix my signature in presence of two witnesses.

WILLIAM R. BAKER.
